UNITED STATES PATENT OFFICE.

ROBERT M. LAMBIE, OF NEW YORK, N. Y.

DESK ATTACHMENT.

SPECIFICATION forming part of Letters Patent No. 245,512, dated August 9, 1881.

Application filed September 26, 1879.

To all whom it may concern:

Be it known that I, ROBERT M. LAMBIE, of New York city, in the county of New York and State of New York, have invented certain new and useful Improvements in Desk Attachments; and I do hereby declare that the following is a full, clear, and exact description thereof.

My invention relates to a desk attachment for chairs and other articles of furniture, for the purpose of affording facility for reading or writing, and for other purposes for which a desk or table may be used.

The invention consists in certain novel details of construction, combination, and operation of various devices, whereby provision is made for adjusting the desk in different positions and at different distances, and for connecting it with different articles of furniture, and whereby several advantages are obtained, all as hereinafter particularly described.

The accompanying drawings illustrate the manner of carrying out my invention.

Figure 1 is a side view, partly in section, representing my improvements when attached to a table or an ordinary chair. Fig. 2 is a detail sectional view of a portion of the desk, taken in the line $x-x$ of Fig. 1. Fig. 3 is a detail sectional view at right angles to Fig. 2, taken in the line $y-y$. Figs. 4, 5, and 6 are detail views hereinafter particularly referred to.

The desk attachment is here shown as consisting of a box or case, A, and an adjustable top, A^2 , arranged to slide thereon and connected thereto in a similar manner to that in which a drawer is connected to a shelf, bench, or table. On the under side of the top A^2 are two braces or cleats, A^3 , which are secured to said top by screws. The screws pass through elongated screw-holes in lugs a^x , extending laterally from the sides of the cleats, by which means provision is made for contraction and expansion of the top A^2 . The cleats A^3 have ribs or tongues a^3 formed on their lower edges, said ribs or tongues projecting inward toward each other and in opposite directions from the lugs a^x , above referred to. These ribs or tongues a^3 engage with grooves a in the sides of the box or case A, (see Fig. 3,) and thus enable the top A^2 to slide on the top of the box or case A.

In order to hold the top A^2 in place on the box or case A a sliding spring-bolt, B, is provided. This bolt works in a casing, B^2 , which is cast in one piece with one of the cleats A^3 , 55 and the nose of the bolt projects from the end of the casing sufficiently to enable it to engage with a series of recesses or sockets, b , in the side of the box or case A. (See Figs. 3 and 4.) By this means the top A^2 may be held in different positions with relation to the box or case A, as illustrated in Figs. 1 and 2. The box or case A serves in place of a drawer for holding writing materials or other articles, and it may be provided with an inkstand, b^x , as 60 shown in Figs. 2 and 3. By providing the means for sliding and retaining the top A the parts may be readily placed in position for writing, as shown in Fig. 2.

For adjusting the desk and retaining it at 70 different angles of inclination, and for rotating it on a center, the following means are employed: On the under side of the box or case A is secured a plate, C, in which are formed sockets c , which serve as bearings for the 75 ends of a shaft, D. The plate C is provided with a semicircular or segmental projection, C^2 , which extends downward at right angles with the surface of the plate proper, and has recesses or depressions c^2 formed on one side. 80 The shaft D is provided with a yoke, D^2 , which surrounds the projection C^2 and carries a set-screw, D^3 , the point of which engages with the depressions c^2 . The yoke D^2 is provided with a nipple or plug, D^4 , which, when engaging 85 with a socket, as hereinafter described, serves as a pivot on which the desk is rotated on a center. This pivot D^4 is intended to always occupy a vertical position when the parts are in place. The desk may be adjusted by loosening the set-screw D^3 and moving the desk to the desired position, where it may be retained by tightening the set-screw, so as to cause its point to engage with the depressions c^2 . 90

The top A^2 is provided with a book-retainer 95 consisting of a strip or bar, E, having on its lower edge dowel-pins e , which engage with sockets in the top A^2 , so that it may be readily placed in position or removed. When the desk is used for reading alone it may be arranged with the book-retainer at the lower end 100 of the top A^2 , as shown in Fig. 1. When used

for writing it may be swung around on its center, so as to bring the book-retainer at the upper end of the top A², as shown in Fig. 2.

When the desk is used for writing the paper-holder may be employed. This consists of a wire, F, bent at an acute angle, and at the angle coiled so as to form a spring, f, from which the shorter end f² projects downward and is inserted in a hole in the bar E and the dowel-pin e, while the longer end is curved sufficiently to enable it to bear upon the paper on the desk with a firm yet elastic pressure. Two or more of these wires may be used, if desired, as shown in Fig. 3, and they may, also, if desired, be used in connection with a book for holding the leaves open.

The desk attachment above described is supported by an adjustable rod or standard, which is connected to a chair, bedstead, or other article by means of a clamp. The rod or standard H carries at its upper end a socket, I, for the reception of the plug or pivot D⁴ of the desk. The socket I is here shown as formed at one end of an arm, h, extending from the standard.

When it is desired to adjust the desk at different distances from the standard H one or more auxiliary arms are employed. The auxiliary arm J has formed at one end a pivot, J², and at the other end a socket, I², which pivot and socket are respectively similar to the pivot D⁴ and socket I, before described, and are of such shape and dimensions that any one of the pivots and any one of the sockets will fit each other. By this means the desk may be rotated on its center and also swung around, so as to place it at any desired distance within the length of the arms.

On referring to Fig. 1 it will be seen that the sockets I and I² are each of a regular conical tapering form, while the plugs or pivots D⁴ and J² are slightly concave around the periphery of each. By this means a double bearing-surface is formed on each pivot—namely, at the points where it engages with the upper and lower edges of the regular conical socket. By this construction the pivot is made to fit sufficiently tight to enable it to work smoothly, and at the same time is prevented from "binding" in the socket.

The clamp shown in Fig. 1 is provided with a fixed jaw, K, a socket, K², a curved arm, K³, and a connecting-bar, K⁴, all cast in one piece. A movable jaw, K⁵, slides on the bar K⁴ in the manner illustrated in Fig. 5. The bearing-surfaces of the jaws K and K⁵ are flat. They are clamped to the chair or other article, as illustrated in section, by means of a set-screw, K⁶, working in the arm K³ and bearing on the movable jaw. The standard H works in the socket K², and is held firmly at any desired height by means of a set-screw, K⁷. I do not claim this particular clamp as my invention.

The clamp shown in Fig. 3 is intended particularly for attachment to a chair of the kind known as "folding chairs," the frames of which are made of bar-iron about one inch and a

quarter wide and one-quarter of an inch thick. This clamp is provided with a fixed jaw, L, a socket, L², a curved arm, L³, and a connecting-bar, L⁴, all cast in one piece. It is also provided with a movable jaw, L⁵, a set-screw, L⁶, for securing it, and a set-screw, L⁷, working in the socket for holding the standard H. In other respects, however, this clamp differs from the one last above described. The fixed jaw L and the movable jaw L⁵ are formed with grooves l in their bearing-surfaces for engagement with the rail l^x of a chair, by which means the clamp is enabled to grasp the same firmly and rigidly, and is positively prevented from slipping. The movable jaw L⁵ has at its rear end two hooks, l⁵, which play on either side of a narrowed portion of the bar L⁴, (see Fig. 6,) so as to guide the jaw and keep it in place. The hooks l⁵ engage with two abutments, l⁴, on the bar L⁴ at a distance from the bearing-surface of the jaw L corresponding with the width of the chair-rail l^x. The set-screw L⁶ engages with the movable jaw L⁵ at a point about midway between the bar L⁴ and the rail l^x, and thus insures the firm and rigid engagement of the parts. This clamp is not claimed in this application, but is made the subject of another application for Letters Patent.

What I claim as new, and desire to secure by Letters Patent, is—

1. In a book-support or desk attachment constructed as described, the metallic braces or cleats A³, provided with the ribs or tongues a³ and the lugs a^x, with elongated screw-holes therein, the casing B², cast in one piece with the metallic brace or cleat A³, and the sliding spring-bolt B, working in the casing B², in combination with the box or ease A and the top A² sliding thereon, substantially as and for the purpose herein described.

2. In a book-support or desk attachment constructed as described, the combination of the box or ease A and top A² sliding thereon, the plate C, attached to box or ease A, and provided with the sockets c c and semicircular projection C², having depressions c² on one side, the shaft D, having the yoke D² and concave plug or pivot D⁴ in one piece therewith, the set-screw D³, working in the yoke D² and engaging with the depressions c², and a conical socket connected with a chair or other article for engagement with said plug or pivot D⁴, substantially as herein described.

3. In a book-support or desk attachment constructed as described, the combination of the pivots D⁴ or J², having their peripheries concave, so as to form a double bearing-surface on each, and the sockets I or I², having a regular conical taper for engagement with said pivots, whereby said pivots are enabled to work freely and smoothly in said sockets without binding therein, substantially as herein described.
